UNITED STATES PATENT OFFICE

2,423,378

HEATER FOR WATER-COOLED ENGINES

Joseph A. Gaschnitz, Munson, Alberta, Canada

Application May 3, 1943, Serial No. 485,522
In Canada May 26, 1942

6 Claims. (Cl. 123—142.5)

1

My invention relates to a heater for the circulating water within the jacket of automobile and truck engines, an object thereof being to provide a device of the character described by means of which the water may be kept hot and the engine warm in frigid weather by novel means and (with respect to the first and more important embodiment) without the employment of electrical power.

A further object of my invention is to provide a device of the character described which can be readily put into operation by the driver of the auto or truck from his position in the cab thereof.

A further object of my invention is to provide a circulating water heater in the form of a small, horizontal, water tube boiler to which is connected, as a unit, a blow torch specially designed for use with the said boiler and including self-igniting mechanism integral with the blow torch.

A further object of my invention is to provide a device having the foregoing objects which is eminently simple to operate, inexpensive to manufacture and which cannot readily become out of order.

With the above more important objects in view and such other minor objects as may appear as the specification proceeds, my invention consists essentially in the arrangement and construction of parts all as hereinafter more particularly described, reference being had to the accompanying drawings, in which—

Figure 1 is a sectional elevation of my device in situ.

Figure 2 is an enlarged sectional elevation of my self-igniting mechanism.

Figure 3 is a section on the line 3—3 of Figure 2.

Figure 4 is a side elevation of my device as a whole and illustrating the same as positioned in an automobile.

Figure 5 is a sectional elevation of an alternative, electrically heated embodiment of my invention.

Figure 6 is a view similar to Figure 4 of the embodiment of my invention illustrated in Figure 5.

In the drawings like characters of reference indicate corresponding parts in the different figures.

2

My invention will preferably, though not necessarily, extend upon either side of the bulkhead 1 of an automobile 2 or a truck, an aperture 3 being formed in the bulkhead for this purpose. It is to be understood that my water tube boiler 4 will be positioned upon the engine side 5 of the bulkhead while the blow torch enumerated 6 as a whole, will be positioned upon the cab side 7 of the bulkhead convenient to the driver.

My water tube boiler 4 comprises the surrounding jacket 8 and the inner jacket 9 interconnected by the passages 10, although at this point, I desire to state that the boiler may be of any configuration as to the arrangement of the tubes therein. However, the foregoing arrangement permits of the distribution of a flame through the center tube 11 and the annular tube 12 as I have indicated by the group of arrows 13, the spent heat from the flame being discharged through the exhaust 14. The boiler which I have described will be connected up to the conventional water jacket of an associated engine 15 at any two convenient points 15' and 15'', preferably by means of flexible hose which will connect with the water intake and discharge nipples 16 and 17 respectively.

The boiler is secured to the bulkhead by means of the surrounding flange 18 which encircles the aperture 3, a sleeve portion 19 projecting through the aperture 3 into the cab below and behind the dashboard 20 to this sleeve, my blow torch 6 is connected.

The blow torch consists of a fuel tank 21 which may also be secured to the bulkhead as at 22 if desired, a conventional pump assembly 23 being associated with the fuel tank. Positioned above the fuel tank is a fire nozzle 24 directed towards the tubes of the boiler, the jet 25 associated with the nozzle, drawing fuel from the tank 21 by means of the supply pipe 26.

The fire nozzle is surrounded by the housing 27 sufficiently provided with air holes 28 to feed the flame from the nozzle 24. The housing is secured to and around the sleeve 19 which sockets into the annular projecting flange 29 of the housing.

Below the nozzle 24 I provide a fuel pan 30 into which a certain amount of fuel will drip when the jet 25 is opened and pressure has been built up in the tank 21 by the pump 23. Associated

with the pan as best illustrated in the accompanying Figure 2 is a wick 31 and a surrounding wick tube 32 the upper end of which projects into the pan and is normally covered by the extinguisher 33.

The extinguisher is mounted for rotation on the stub shaft 34 (see Figure 3) which is journalled in the pair of upstanding brackets 35 secured to the pan 30. Within the interior of the extinguisher I locate a flint-wheel 36, while against one wall of the extinguisher is mounted a small pinion 37, the extinguisher, flint-wheel and pinion rotating as a unit.

In mesh with the pinion 37 is a rack 38 connected to the push rod and finger disc 39, the rod extending through the projecting sleeve 40 on the pan, which sleeve contains a small coil spring 41.

An upwardly spring pressed flint 42 bears against the flint-wheel 36 and is contained within the receptacle 43 and from the foregoing, it will clearly be recognized that upon the impression of linear movement against the push rod in the direction of the arrow 43 (Figure 2), the pinions, flint-wheel and snuffer will be rotated in a clockwise direction as indicated by the numeral 44 so that the upper end of the wick 31 is uncovered, while, at the same time, a spark is thrown against it.

The ignited wick sets fire to the fuel within the pan 30, which in turn ignites the fuel proceeding from the jet 25 under pressure, and thus the blow torch is ignited. The contents of the pan are soon used up and a clean, hot flame is soon playing on the surfaces of the fire tubes 11 and 12.

The alternative, electrically heated embodiment of my heater as illustrated in the accompanying Figures 5 and 6, may be located upon either side of the bulkhead 1 although I have shown it connected upon the cab side 7. For this embodiment, I prefer to employ a vertical arrangement of tubes, although I do not wish to be restricted to a vertical arrangement.

The vertical arrangement which I have shown in the accompanying Figure 5 is similar to the horizontal arrangement of Figure 1 for which reason, the same numerology has been employed. Intake and return water nipples 45 and 46 respectively project through the bulkhead to be connected via a hose or some other suitable connection to the water jacket of the associated engine.

Beneath the arrangement of tubes, is a heating chamber 47 containing an electrical element or resistance 48. The heat from the resistance rises through the tubes 11 and 12, being allowed to escape through the exhaust port 49, and thus, it will be seen that I have provided a simple and effective electrical embodiment which can readily be connected and disconnected at the socket 50 by the operator of the automobile or truck.

In conclusion, I would particularly point out that while my herein described device obviously operates in a highly efficient manner to maintain the temperature of water in an associated engine water jacket, the same is primarily designed, and conspicuously useful for heating the water in sub-zero weather, and after an automobile, for instance, has been exposed to such weather so that it is of the same temperature. It will be understood that in winter, the engine jacket will contain a mixture of water and anti-freeze which, as is well known, does not freeze solid, but only

congeals into a semi-fluid mass at the lowest temperatures likely to be encountered.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this invention may be made within the scope of the accompanying claims without departing from the spirit and scope of the same it is intended that all matter contained in the accompanying specification shall be interpreted as illustrative only and not in a limiting sense and I desire only such limitations placed thereon as justice dictates.

What I claim as my invention is:

1. An auto and truck engine circulating water heater, comprising in combination, a horizontal water tube boiler having a water inlet and a water return communicating with the jacket of said engine, a horizontal blow torch attached to said boiler and lying in the horizontal bounding planes of said boiler, and self igniting mechanism integral with said blow torch.

2. An auto and truck engine circulating water heater, comprising in combination, a water tube boiler secured to the bulkhead of said auto or truck and upon the engine side of said bulkhead and a blow torch in communication with the fire tubes of said boiler, said blow torch being located upon the cab side of said bulkhead.

3. An auto and truck engine circulating water heater, comprising in combination, a water tube boiler secured to the bulkhead of said auto or truck and upon the engine side of said bulkhead, a blow torch in communication with the fire tubes of said boiler, said blow torch being located upon the cab side of said bulkhead and self-igniting mechanism integral with said blow torch.

4. An auto and truck engine circulating water heater, comprising in combination, a horizontal water tube boiler secured to the bulkhead of said auto or truck upon the engine side of said bulkhead, said bulkhead being provided with an aperture, said boiler surrounding said aperture, a blow torch attached to said boiler but being located upon the cab side of said bulkhead and self-igniting mechanism integral with said blow torch.

5. An auto and truck engine circulating water heater, comprising in combination, a horizontal water tube boiler having a water inlet and a water return communicating with the jacket of said engine or heater, said boiler being secured to the bulkhead of said auto or truck and around an aperture provided therein, a blow torch designed for connection to said boiler as a removable component of a unit comprising said boiler and said blow torch, said blow torch being positioned upon the cab side of said bulkhead and having a housing surrounding the fire nozzle thereof to isolate the flame therefrom and enclose it within the unit.

6. An auto and truck engine circulating water heater, comprising in combination, a horizontal water tube boiler having a water inlet and a water return communicating with the jacket of said engine or heater, said boiler being secured to the bulkhead of said auto or truck and around an aperture provided therein, a blow torch designed for connection to said boiler as a removable component of a unit comprising said boiler and said

blow torch, said blow torch being positioned upon the cab side of said bulkhead and having a housing surrounding the fire nozzle thereof to isolate the flame therefrom and enclose it within the unit and self-igniting mechanism integral with said blow torch.

JOSEPH A. GASCHNITZ.
